(57) CLAIM

The ornamental design for a combined tea table with loudspeaker, as shown and described.

DESCRIPTION

FIG. 1 is a front and top perspective view of a combined tea table with loudspeaker, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detailed view taken from the encircled area 9 indicated in FIG. 2; and,

FIG. 10 is an enlarged detailed view taken from the encircled area 10 indicated in FIG. 3.

The broken lines in the figures illustrate portions of the combined tea table with loudspeaker that form no part of the claimed design.
